Inventor
J. Mitchell,

By Clarence A. O'Brien.

Attorney

UNITED STATES PATENT OFFICE.

JULIUS MITCHELL, OF CLEVELAND, OHIO. **BEST AVAILABLE COPY**
PENCIL.

Application filed February 12, 1926. Serial No. 87,804.

This invention relates to new and useful improvements in pencils, and has for its primary object to provide such an article including a hollow casing within which is adapted to be disposed a strip of lead that may be readily fed from the casing at the point end thereof whenever the point becomes worn without requiring the frequent sharpening of the pencil or without requiring the manipulation of complicated mechanism as now employed in conjunction with the types of mechanical pencils now upon the market.

The primary object of the invention is to provide a relatively inexpensive, but efficient form of pencil and whereby the single strip of lead may be quickly fed therefrom and wherein the lead may be used when necessary.

With the foregoing and other objects in view as the nature of the invention will be better understood, the same comprises the novel form, combination and arrangement of parts hereinafter more fully described and shown in the accompanying drawing and claimed.

In the drawing wherein like reference characters indicate corresponding parts throughout the several views:—

Figure 1 is a front elevation of a pencil constructed in accordance with my invention,

Fig. 2 is a detail vertical section thereof, and

Fig. 3 is a detail longitudinal section taken substantially upon the line 3—3 of Fig. 1.

Now having particular reference to the drawing, my novel pencil constitutes the provision of a hollow casing 5 of suitable material, provided with a pointed end 6 as its lower end, through which extends a bore 7 in communication with the interior of the casing as clearly shown in Fig. 2.

Said casing 5 is formed throughout substantially its entire length with a slot 8 that opens at the upper end of the casing within which is adapted to be exposed a rubber eraser carrying enclosing plug 9.

Frictionally disposed within the casing and adapted to be forcibly slid upwardly and downwardly therein is a sleeve 10 preferably of wood and surrounding the lower

portion of which is a reinforcing metallic band 11. Adapted to be frictionally engaged within the lower end of the said sleeve is one end of a lead strip 12 which is adapted to frictionally engage through the bore 7 in the pointed end 6 of the casing 5, Fig. 2.

Frictionally engaging the exterior of the casing 5 is a ring 13 preferably of the same material as the casing, the same being concentric with the beforementioned sleeve 10 and secured thereto in spaced concentric relation through the medium of a screw 14, 65 the shank portion of which extends through the ring and into the sleeve and slides within the slot 8 of the casing 5, it being apparent that a manipulation of the ring 13 will cause movement of the lead carrying sleeve 10 consequently leading the lead into or out of the casing as desired.

The ring 13 is formed at its front side, and at its lower edge with an extension 15 that covers the slot 8 forwardly of the sleeve 10 in order that said sleeve may not be viewed exteriorly of the pencil.

It will thus be seen that I have provided a highly novel, simple and efficient form of pencil, one that may be manufactured and marketed in an inexpensive manner, and that is not liable to easily become out of order, and one wherein the lead may be fed into or out of the casing of the pencil in a simple and quick manner.

Having thus described my invention, what I claim as new and desire to secure by Letters Patent is:—

In a pencil of the class described, a hollow casing open at both ends, one end thereof being beveled to simulate a pencil point, the bore of the beveled end portion of the hollow casing being reduced, said casing being provided with a slot throughout substantially the entire length, one end thereof opening at the end of the casing remote from said point, a sleeve frictionally and slidably disposed in the casing, a lead fitted at one end within the sleeve and adapted to be expelled at its other end outwardly of the pencil casing through the reduced bore, a ring surrounding the casing in concentric relation with said sleeve, the portion of said ring which extends across the slot being of

substantially the same width as the length of said sleeve to conceal the same, a pin having its shank extending through the widened portion of the ring and through the slot in the casing, the inner end of said pin being threaded into the sleeve whereby said sleeve and said lead may be moved in either direc-

tion, and removable means within the other open end of the casing for limiting the movement of the lead carrying sleeve in said 19 direction.

In testimony whereof I affix my signature.

JULIUS MITCHELL.
